US00D975053S

(12) **United States Design Patent** (10) **Patent No.:** **US D975,053 S**
Ma (45) **Date of Patent:** **** Jan. 10, 2023**

(54) **LOUDSPEAKER**

(71) Applicant: **SHENZHEN GEEKBUY E-COMMERCE LIMITED COMPANY**, Shenzhen (CN)

(72) Inventor: **Kuiyuan Ma**, Shenzhen (CN)

(73) Assignee: **SHENZHEN GEEKBUY E-COMMERCE LIMITED COMPANY**, Shenzhen (CN)

(**) Term: **15 Years**

(21) Appl. No.: **29/797,302**

(22) Filed: **Jun. 30, 2021**

(51) LOC (14) Cl. **14-01**

(52) U.S. Cl.

USPC **D14/214**

(58) **Field of Classification Search**

USPC D10/15, 104.1, 106.1; D14/195, 204, D14/215, 210, 214, 168, 170, 225, 188, D14/356, 203.3, 211, 171, 209.1, 496; D23/364

CPC H04R 1/02; H04R 1/026; H04R 9/06

(57) **CLAIM**

The ornamental design for a loudspeaker, as shown and described.

DESCRIPTION

FIG. 1 is a perspective view of a loudspeaker showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1; and,

FIG. 11 is an enlarged view of portion 11 shown in FIG. 2. The broken lines in the drawings depict portions of the loudspeaker that form no part of the claimed design.

1 Claim, 11 Drawing Sheets
